FREQUENCY CHANGER

Ernest G. Linder, Princeton, N. J., assignor to
 Radio Corporation of America, a corporation
 of Delaware

Application October 23, 1945, Serial No. 623,947

18 Claims. (Cl. 250—36)

1
 My invention relates to electron discharge devices and associated circuits, more particularly to such devices and circuits useful at ultra high frequencies and capable of frequency change.

The present application is directed to an improved device of the kind described and claimed in patent application Serial No. 385,447, filed March 27, 1941, now Patent No. 2,401,945, dated June 11, 1946, and assigned to the same assignee as the present application.

It is a principal object of my invention to provide an improved type electron discharge device and associated circuit useful at ultra high frequencies and employing cavity resonators, and more particularly to provide such a device and circuit useful as a frequency changer.

The novel features which I believe to be characteristic of my invention are set forth with particularity in the appended claims, but the invention itself will best be understood by reference to the following description taken in connection with the accompanying drawing in which Figure 1 is a partially schematic longitudinal section of an electron discharge device and associated circuit made according to my invention, Figure 2 is a graph showing the principles of operation of my invention, and Figure 3 is a partially schematic longitudinal section of a modification of the device shown in Figure 1.

In a device made according to my invention an electron beam is modulated at a predetermined fundamental high frequency to provide equally spaced bunches of electrons. The bunches are then subjected to a high frequency field of a lower frequency and having a predetermined voltage characteristic for successively and at increased voltage increments accelerating the bunches of electrons to compress the electron bunches into spaced groups of bunches within a field-free space. The spacing between electron bunches in each group becomes decreased in this field-free space. The groups of compressed bunches are then utilized to excite an output resonator at a higher frequency than the fundamental frequency initially applied to the electron stream.

In Figure 1 is shown a device and circuit made according to my invention. It may include an evacuated elongated envelope 10 having at one end an indirectly heated cathode 11 and at the other a collector 12. Adjacent the cathode is a control electrode 13 for modulating the electron stream. Between the control electrode 13 and the collector 12 there is a hollow tubularly shaped electrode 14 having an aperture 16 adjacent the

2
 electrode 13 and a partition 15, the partition and the end of the electrode 14 adjacent collector 12 being provided with apertures and reentrant portions 17 and 18 to provide a gap past which the compressed groups of electrons are directed. In effect the portion of the electrode 14 adjacent the collector 12 provides a cavity resonator 19 having an output coupling loop 19'. A magnetic coil 20 may be used for maintaining the beam of electrons focused.

A first high frequency oscillator 21 is connected between the cathode 11 and the control electrode 13 for applying a voltage of one frequency f_1 to the electrode 13 to provide equally spaced electron bunches as indicated in the top portion I_p of the graph, Figure 2. Biasing voltage source 23 biases the tube to cut-off when no oscillator voltage is applied. A second oscillator 22 is connected between the cathode and the electrode 14 through an accelerating biasing voltage source 24. The frequency f_2 of this second oscillator 22 and the voltage wave form is as indicated in the second line of the graph, Figure 2. In the particular case shown the frequency f_2 is one-quarter the frequency of the first oscillator. This second frequency can be varied so that the ratio of frequencies may be any number, so long as the frequency of the oscillator 22 is less than that of the oscillator 21. The result of applying this voltage E_{22} is to compress the electron bunches into groups as is shown in the lower part of the graph, Figure 2, so that in effect groups of electrons are produced with the spacing between the bunches in each group reduced. The time elements, voltages and spacings are so chosen that the bunches of each group of electrons have a transit time past the gap in the resonator 19 and a phase relationship necessary to excite this resonator at a higher frequency than that of oscillator 21. The collector 12 is maintained at a positive potential with respect to the cathode by a voltage source 25.

In more detail, electron bunches leave the electrode 13 spaced at even intervals as indicated by I_p . The accelerating voltage applied to the electrode 14 is of saw-tooth shape and preferably parabolic since this is the type of voltage form necessary to produce the results desired. For example, consider the case in which each bunch is given a velocity increment Δv in excess of the preceding bunches. The resulting velocities will be

$$\begin{aligned} v_1 &= v_1 \\ v_2 &= v_1 + \Delta v \\ v_3 &= v_1 + 2\Delta v \end{aligned}$$

v_n is equal to $v_1 + (n-1)\Delta v$. It will thus be seen that as each bunch emerges into the space between electrode 13 and the aperture 16 it will receive a voltage increment such that each successive pulse is subjected to a successively increasing accelerating voltage, the last bunch crossing this space when the potential of electrode 14 is greatest receiving the greatest acceleration. Each of the bunches on entering the field-free space within the electrode 14 retains the velocity it had on passing through the aperture 16 so that the bunches approach closer to each other as they reach the partition 15, the faster bunches overtaking the slower bunches and forming spaced groups of closely spaced bunches. The parameters are so chosen that the bunches of each group pass the gap between the portions 17 and 18 of resonator 19 in proper phase to continuously excite the resonator, the spacing between adjacent bunches being such that the resonator oscillates at its resonant frequency through at least one cycle before the next bunch arrives. The resonator 19 is so constructed that its resonant frequency is substantially higher than that of oscillator 21.

In Figure 3 I have shown a modification of the device shown in Figure 1. In this figure similar numerals apply to similar parts as in Figure 1. Improvement in this form lies in introducing means for shortening the necessary compression space, to permit shortening the electrode 14. This is especially useful when large numbers of bunches are compressed into groups. I do this by providing a retarding field introduced by successive decelerating electrodes 30 which are maintained at successively lower constant potentials by means of voltage source 32 and voltage divider 31. This reverse field decelerates the slower bunches to a greater amount than the faster bunches, thus increasing the velocity difference therebetween, which reduces the drift distance required for a given degree of compression of the bunches, that is, for a given output frequency. If desired a focusing electrode 34 may be positioned between resonator 19 and the last decelerating electrode 30 at a voltage maintained at the desired level by voltage source 35.

While I have indicated the preferred embodiments of my invention of which I am now aware and have also indicated only one specific application for which my invention may be employed, it will be apparent that my invention is by no means limited to the exact forms illustrated or the use indicated, but that many variations may be made in the particular structure used and the purpose for which it is employed without departing from the scope of my invention as set forth in the appended claims.

What I claim as new is:

1. A frequency changer including means for supplying a stream of electrons along a predetermined path, means for modulating said electron stream at a predetermined frequency to produce equally-spaced bunches of electrons of substantially the same velocity along said path, means for accelerating a plurality of successive bunches to increasingly greater velocities, means causing compression of said differentially accelerated bunches into a group of closely-spaced bunches, and tuned means for extracting energy from said group of closely-spaced bunches at a substantially higher frequency than said predetermined frequency.

2. A frequency changer including means for supplying a stream of electrons along a prede-

termined path, means for modulating said electron stream at a predetermined frequency to produce equally-spaced bunches of electrons of substantially the same velocity along said path, means for subjecting a plurality of said bunches to an electric field of increasing strength for accelerating successive bunches at increasingly greater increments, means providing a shielded space along said path for receiving said differentially accelerated bunches for causing compression of said bunches into a group of closely-spaced bunches, and tuned means for extracting energy from said group of closely-spaced bunches at a substantially higher frequency than said predetermined frequency.

3. A frequency changer including means for supplying a stream of electrons along a predetermined path, means for modulating said electron stream at a predetermined frequency to produce equally-spaced bunches of electrons of substantially the same velocity along said path, periodic means for accelerating successive bunches of electrons in each cycle of said periodic accelerating means to successively higher velocities, means for compressing successive bunches of said differentially accelerated bunches in each cycle into a group of closely-spaced bunches, and tuned means for extracting energy at a substantially higher frequency than said predetermined frequency from each group of closely-spaced bunches of electrons.

4. A frequency changer including means for supplying a stream of electrons along a predetermined path, means for modulating said electron stream at a predetermined frequency to produce equally-spaced bunches of electrons of substantially the same velocity along said path, means for subjecting said bunches of electrons to a periodic electric field of substantially lower frequency than said predetermined frequency and increasing in strength with time throughout the major portion of each cycle thereof for accelerating successive bunches in each cycle thereof to successively greater velocities, means providing a shielded space along said path for receiving said differentially accelerated bunches for compressing said bunches in each cycle into a group of closely-spaced bunches, and tuned means for extracting energy from each group of closely-spaced bunches at a substantially higher frequency than said predetermined frequency.

5. A frequency changer comprising means for supplying a stream of electrons along a predetermined path, means including a control electrode in said path for modulating said electron stream at a predetermined frequency to produce equally-spaced electron bunches of substantially the same velocity along said path, a second electrode in said path beyond said control electrode, a source of potential of substantially lower frequency than said predetermined frequency and having a wave form which increases in amplitude with time during the major portion of each cycle thereof and connected to said second electrode for accelerating successive bunches in each cycle at increasingly greater increments, means providing a shielded space along said path for receiving said differentially accelerated bunches for causing said bunches in each cycle to form a group of closely spaced bunches, and tuned means for extracting energy from said closely spaced bunches of each group at a higher frequency than said predetermined frequency.

6. A frequency changer according to claim 5.

wherein said source has a saw-tooth parabolic wave form of increasing amplitude with time.

7. A frequency changing system including means comprising a cathode for supplying a stream of electrons along a predetermined path, a control electrode adjacent said cathode, a source of potential of a predetermined high frequency connected to said control electrode for modulating said stream to produce equally-spaced bunches of electrons along said path, a second electrode in the path of said equally-spaced bunches of electrons, a second source of potential having a frequency substantially less than said predetermined frequency and having a wave form of saw-tooth parabolic shape and connected to said second electrode for accelerating successive equally-spaced bunches in each cycle to increasingly higher velocities, a drift tube providing a shielded space along said path through which said differentially accelerated bunches of electrons are directed, whereby said bunches become compressed into groups of closely-spaced bunches in traversing said space, and tuned means for extracting energy from said closely-spaced bunches and including a cavity resonator disposed in said path, the fundamental frequency of said resonator being substantially higher than said predetermined frequency.

8. A frequency changer according to claim 7 wherein said drift tube comprises a tubular member having aligned apertures at its ends and including said output cavity resonator within said tubular member.

9. A frequency changer according to claim 8, wherein said tubular member has a partition therein intermediate its ends, said partition having an aperture aligned with said end apertures and being more closely adjacent the end of said tubular member remote from said second electrode, said cavity resonator being formed by said partition and tubular member.

10. An electron discharge device having a cathode for supplying electrons along a predetermined path, means in said path for applying an electric field of one high frequency to said electrons to obtain equally spaced bunches of electrons of substantially the same velocity, a second means in said path for applying an accelerating electric field having a high frequency substantially less than said one frequency to said equally spaced bunches of electrons substantially for differentially accelerating successive bunches, means providing a shielded space through which said differentially accelerated bunches of electrons are directed to compress said bunches in each cycle into a group of closely spaced bunches, means in said space for applying a decelerating field to said bunches of electrons, and tuned means for extracting energy from decelerated compressed groups of electrons at a frequency which is substantially higher than said one frequency.

11. An electron discharge device having a cathode for supplying electrons along a predetermined path, means for collecting said electrons, means including a control electrode adjacent said cathode in the path of said electrons for applying a modulating electric field of one high frequency to said electrons for providing equally spaced electron bunches, a second electrode positioned between said control electrode and said collector and comprising a tubular member having a partition intermediate the ends thereof, the ends of said tubular electrode and said partition having aligned apertures, said partition being more close-

ly adjacent the end of said tubular member adjacent said collector and providing a cavity resonator within said tubular member, the portion of said tubular member between the end thereof adjacent said control electrode and said partition providing a continuous drift space, and means for applying to said tubular member a modulating potential having a high frequency substantially less than said one frequency, whereby said bunches of electrons become compressed into groups of closely spaced bunches within said drift space prior to passage through said apertured partition.

12. An electron discharge device having a cathode for supplying electrons along a predetermined path, means including a control electrode adjacent said cathode in the path of said electrons for applying a modulating electric field of one high frequency to said electrons for providing equally spaced electron bunches, a second electrode positioned in the path of said bunches and comprising a tubular member extending along said path and having aligned apertures at its ends and including a cavity resonator within said tubular member, the portion of said tubular member between the end thereof nearest the control electrode and said cavity resonator providing a continuous drift space, and means for applying to said second cathode a modulating potential having a high frequency less than said one frequency whereby said bunches of electrons become compressed into a group of closely spaced bunches within said drift space prior to passage through said resonator.

13. An electron discharge device having a cathode for supplying electrons along a predetermined path, means including a control electrode adjacent said cathode in the path of said electrons, for applying a modulating electric field of one high frequency to said electrons for providing equally spaced electron bunches, a second electrode positioned in the path of said bunches and comprising a tubular member through which said electron bunches pass, and means for applying to said tubular member a modulating potential having a high frequency potential less than said one frequency whereby said bunches of electrons in each cycle become compressed into groups of closely spaced bunches within said tubular member, and means within said tubular member for decelerating each bunch of electrons and a cavity resonator through which said groups of closely spaced bunches are directed to excite said resonator at a frequency substantially greater than said one frequency.

14. The method of generating ultra high frequency oscillations which includes the steps of generating an electron beam, modulating said beam at one frequency to obtain equally spaced bunches of electrons, subjecting a plurality of successive bunches of electrons to successively increasing accelerating forces, passing said differentially accelerated bunches of electrons through a shielded space to cause said bunches to form a group of closely spaced bunches, and extracting energy from said grouped bunches of electrons at a frequency higher than said one frequency.

15. A method of generating ultra high frequency oscillations which includes the steps of generating an electron stream, modulating said stream at one frequency to obtain equally spaced bunches of electrons, periodically subjecting successive bunches to increasingly greater accelerating forces during each period, passing said differentially accelerated bunches of electrons

through a shielded space to cause said bunches to form spaced groups of closely spaced bunches, and extracting energy from each group of closely spaced bunches at a higher frequency than said one frequency.

16. A method of generating ultra high frequency oscillations which includes the steps of generating an electron beam, modulating said beam at one frequency to obtain equally spaced bunches of electrons, subjecting a plurality of successive bunches to increasingly greater accelerating forces, whereby the last bunch of each cycle is given the greatest velocity, passing said differentially accelerated bunches of electrons through a shielded space to cause said bunches to form a group of closely spaced bunches, subjecting said accelerated bunches while in said space to decelerating forces to reduce the required drift distance for grouping, and extracting energy from said closely spaced bunches at a higher frequency than said one frequency.

17. A frequency changer according to claim 9, including a series of decelerating electrodes insulatedly mounted along said path and within said tubular member between said second elec-

trode and said partition, and means for maintaining said decelerating electrodes at such potentials that the same reverse field may be applied to all of said bunches to decelerate said bunches as they pass through said drift tube.

18. A frequency changer according to claim 5, further including means in said shielded space for applying the same reverse electric field to all of said bunches to decelerate said bunches as they pass through said space.

Certificate of Correction

Patent No. 2,508,645

May 23, 1950

ERNEST G. LINDER

It is hereby certified that error appears in the printed specification of the above numbered patent requiring correction as follows:

Column 5, line 51, strike out the word "substantially"; column 6, line 29, strike out "cathode" and insert instead *electrode*; line 46, for "potential" read *substantially*;

and that the said Letters Patent should be read as corrected above, so that the same may conform to the record of the case in the Patent Office.

Signed and sealed this 30th day of January, A. D. 1951.
